UNITED STATES PATENT OFFICE

156,844

SERVING TRAY OR SIMILAR ARTICLE

Nathan W. Roop, Columbus, Ohio, assignor to Columbus Plastic Products Inc., Columbus,
Ohio, a corporation of Ohio

Application June 26, 1948, Serial No. 147,225

Term of patent 14 years

(Cl. D44—10)

To all whom it may concern:

Be it known that I, Nathan W. Roop, a citizen of the United States, residing at Columbus, in the county of Franklin and State of Ohio, have invented a new, original, and ornamental Design for a Serving Tray or Similar Article, of which the following is a specification, reference being had to the accompanying drawing, forming a part thereof.

Fig. 1 is a top plan view of a serving tray or similar article, showing my new design;

Fig. 2 is a transverse vertical sectional view taken along the line 2—2 of Fig. 1;

Fig. 3 is a fragmentary vertical sectional view taken along the line 3—3 of Fig. 1.

I claim:

The ornamental design for a serving tray or similar article, substantially as shown.

NATHAN W. ROOP.
